OTHER PUBLICATIONS

"All Field Series" Fixtures shown in the Ephesus Lighting Brochure No. BR507007EN dated Jan. 2017. (8 pages).*

Primary Examiner — Clare E Heflin

(74) Attorney, Agent, or Firm — Fox Rothschild LLP

(57) **CLAIM**

The ornamental design for a lighting fixture, as shown and described.

DESCRIPTION

FIG. 1 is first side of a lighting fixture.

FIG. 2 is a second side of a lighting fixture from a first side.

FIG. 3 is a front view of a lighting fixture from a second side.

FIG. 4 is a rear view of a lighting fixture.

FIG. 5 is a bottom view of a lighting fixture.

FIG. 6 is a top view of a lighting fixture.

FIG. 7 is a first perspective view of a lighting fixture; and,

FIG. 8 is a second perspective view of a lighting fixture. The broken lines shown on the drawings depict portions of the lighting fixture that form no part of the claimed design.

1 Claim, 8 Drawing Sheets
